UNITED STATES PATENT OFFICE

2,553,282

GARMENT HANGER

Edward Sokolik, New Brighton, Minn.

Application May 6, 1946, Serial No. 667,514

13 Claims. (Cl. 223—91)

1

My invention relates to garment hangers and has for an object to provide a garment hanger on which both coats and trousers and other garments may be conveniently hung.

An object of my invention resides in providing a garment hanger on which two pair of trousers may be supported.

Another object of my invention resides in providing a garment hanger on which the trousers may either be hung from the cuffs or may be supported in folded relation.

A still further object of my invention resides in providing a garment hanger in which two spaced reaches are employed whereby extended area is provided for supporting the garments in folded relation.

Another object of my invention resides in providing two arms forming the supports for the trousers, said arms having connecting members therebetween forming with said arms bights for the endwise reception of the trousers.

Another object of the invention resides in providing fastening means for the ends of the arms, said fastening means being disengageable upon upward movement of the arms upon which the garment is hung.

A still further object of the invention resides in providing a garment hanger which can be constructed from a single piece of wire.

A feature of the invention resides in providing a garment hanger formed with a shoulder support having a loop at the end of the same and further formed with a pendant extending downwardly from the inner portion of the loop and forming a re-entrant angle therewith.

A still further object of the invention resides in constructing one of the arms with a finger piece disposed in said angle and serving to disengage the fastening means upon movement of the finger piece within said angle.

Other objects of the invention reside in the novel combination and arrangement of parts and in the details of construction hereinafter illustrated and/or described.

In the drawings:

Fig. 1 is a side elevational view of a garment hanger illustrating an embodiment of my invention.

Fig. 2 is a plan view of the upper portion of the hanger.

Fig. 3 is an end elevational view of the hanger shown in Fig. 1.

Fig. 4 is a plan sectional view taken on line 4—4 of Fig. 1.

Figs. 5, 6, 7, 8 and 9 are views similar to Fig. 4 showing modifications of the invention.

2

The form of the invention illustrated in Figs. 1 to 4 is constructed from a single length of wire which is bent to form the various parts of the hanger. The hanger illustrated comprises two arms 31 and 32 which consist of parallel reaches 16 and 17. The reaches 17 of arms 31 and 32 are connected together by means of a connecting member 19 through bends 18 in the wire from which the said hanger is constructed and which provides bights 20 between the reaches 17 and the connecting member 19. These bights are elongated and serve to receive trousers and other garments which may be slid into said bights through the ends thereof opposite the bends 18 when the bights are opened by springing the arms apart. The two reaches 16 and 17 are formed by bends 14 at the ends of said arms and which serve as finger pieces for a purpose to be presently described.

20 The reaches 16 are connected to pendants 22 which issue from the upper portions of loops 24 formed at the ends of shoulder supports 23. The loops 24 give the supports 23 increased area at the point of engagement of the shoulder 25 support with the shoulders of the garment. The upper ends of the shoulder support 23 are twisted together as designated at 25 to form a shank 33.

One end of the wire from which the garment hanger is constructed is bent to form a hook 26 having appreciable lateral extent and by means of which the garment hanger may be supported on a support having appreciable transverse extent such as a pair of spaced rods. The other end of the wire is bent to form a sharp hook 27 by means of which the garment hanger may be hung on a nail or other object of small dimensions. Issuing outwardly from hook 27 is a curved portion 28 which forms an enlargement of said hook adapted to hook over a pole or other similar supporting structures.

30 The two arms 31 and 32 are fastened together by means of fasteners 34 and 39. The said fasteners being identical in construction, only the fastener 34 will be described in detail.

35 This fastener consists of a lug 15 formed in the reach 16 of arm 32 by providing a U-shaped bend in said reach extending upwardly from the same. The said lug is adapted to be engaged, by an eye 35 formed on the reach 17 of arm 31.

50 The eye 35 in the form of the invention shown in Figs. 1 to 4 may be constructed by merely offsetting a portion of the reach 17 or the same may be completely closed if desired. In operation the eye 35 is hooked over the lug 15 and may be disengaged therefrom by upward movement of the finger piece 14 formed on arm 31.

The form of the invention shown in Fig. 5 is similar to that shown in Fig. 4 and the same reference numerals to which the suffix "a" has been added will be used to designate the corresponding parts. It will be noted that this form of the invention differs from that shown in Fig. 4 only in that the reaches 16a and 17a of the two arms 31a and 32a have been twisted together to increase the strength of the hanger.

In the form of the invention shown in Fig. 6, the same reference characters with the suffix "b" have been used to indicate the parts corresponding with those of the form shown in Fig. 4. It will be noted that the only difference between this form of the invention and that shown in Fig. 4 is that the inner reaches 17 have been omitted so that a single thickness of wire is provided for each garment when the same is supported by the cuffs. With the device shown in Fig. 6, only a single garment may be supported in folded relation.

The device shown in Fig. 7 is similar to that shown in Fig. 4 and the same reference numerals to which the suffix "c" has been added will be used to designate the corresponding parts. This device differs from that in Fig. 4 in that the connecting member 19 has been omitted.

The structure shown in Fig. 8 is similar to that shown in Fig. 4 and the same reference characters to which the suffix "d" has been added will be used to designate the corresponding parts. In this form of the invention the connecting member 19 and the reaches 17 of the arm 32d have been omitted. With this construction, only a single garment may be supported by the hanger. The said garment, however, when folded, will have support through the two reaches 16d and 17d of arm 31d.

In the form of the invention shown in Fig. 9, the same reference characters to which the suffix "e" has been added will be used to designate the corresponding parts. This form of the invention is the same as that shown in Fig. 8, except that the reaches 16e and 17e of arm 31e have been twisted.

The operation of the invention is obvious. In disengaging the fasteners 34, the eyes 35 may be disengaged from the lugs 15 by moving the finger pieces 14 upwardly within the angles 36 formed between the loops 24 and the pendants 22. The arms 31 and 32 may then be spread apart to open up the bights 20 and to permit of inserting of the garments therein. After positioning the garments, the parts are fastened together by hooking the eyes 35 back upon the lugs 15. It will be noted that two garments may be supported, and in the case of trousers or skirts, the same may be supported by the cuffs or waist bands as desired, or said garments may be folded over and caused to rest upon the arms 31 and 32. Coats and similar garments are supported by the shoulder support 23 in the customary manner.

The advantages of my invention are as follows. The garment hanger can be constructed from a single piece of wire at an economical cost. With my invention two pairs of trousers can be supported. The fastening means are disengaged by upward movement of the arms of the garment hanger, whereby the weight of the garment will hold the parts secured to one another. If it is desired to fold the garments, the same may be hung in certain forms of the invention on two bars which increase the supporting area and prevent sharp creases in the garment. The dual garment supports can be operated one at a time,

thereby facilitating the use of the device. With my invention extended surface is formed on the shoulder supports, thereby preventing sharp creases in the coat or other garments supported thereon.

Having described my invention, what I claim as new and desire to protect by Letters Patent is:

1. In a garment hanger, a hook, shoulder supports connected to said hook and extending angularly outwardly therefrom, arms extending inwardly from said shoulder supports and along each other, one of said arms having a reverse bend providing an elongated bight open at the other end for the endwise reception of a garment, and fastening means for said arm at the open end of said bight for securing said arms together and for closing said bight.

2. In a garment hanger, a hook, shoulder supports connected to said hook and extending angularly outwardly therefrom, arms extending inwardly from said shoulder supports and along each other, one of said arms comprising two bars over which a folded garment may be placed, and the other arm including a clamp bar movable toward the first arm and fastening means between the arms.

3. In a garment hanger, a hook, shoulder supports connected to said hook and extending angularly outwardly therefrom, arms extending inwardly from said shoulder supports and along each other, one of said arms having a reverse bend providing an elongated bight open at the other end for the endwise reception of a garment, the other of said arms having a similar reverse bend providing an elongated bight open at the opposite end and fastening means for securing the arms together and for closing the open ends of both of the bights.

4. In a garment hanger, a hook, shoulder supports connected to said hook and extending angularly outwardly therefrom, arms extending inwardly from said shoulder supports and along each other, one of said arms having a reverse bend providing an elongated bight open at the other end for the endwise reception of a garment, the other of said arms having a similar reverse bend forming an elongated bight open at the other end for the endwise reception of a garment, and fastening means for each of said arms at the bends therein for securing each of said arms to the other arm.

5. In a garment hanger, a hook, shoulder supports connected to said hook and extending angularly outwardly therefrom, arms extending inwardly from said shoulder supports and along each other, one of said arms having a reverse bend providing an elongated bight open at the other end for the endwise reception of a garment, the other of said arms having a similar reverse bend forming an elongated bight open at the other end for the endwise reception of a garment, a connecting member between said bights and common to both of said bights, and fastening means for said arms at the bends therein, for securing said arms together.

6. In a garment hanger, a hook, shoulder supports connected to said hook and extending angularly outwardly therefrom, arms extending inwardly from said shoulder supports and along each other, said arms being constructed of an elongated flexible member bent back upon itself to form coextensive reaches providing a support of double width on which folded garments may be placed, said reaches forming a bight with one another at one end thereof and means for se-

curing the opposite end of said reaches together to close said bight.

7. In a garment hanger, a hook, shoulder supports connected to said hook and extending angularly outwardly therefrom, arms extending inwardly from said shoulder supports and along each other, said arms being constructed of an elongated flexible member bent back upon itself to form coextensive reaches providing a support of double width on which folded garments may be placed, one of said arms being connected to one of the reaches of the other arm and forming therewith a bight in which a garment may be disposed, and means for securing the arms together to close the bight.

8. In a garment hanger, a hook, shoulder supports connected to said hook and extending angularly outwardly therefrom, loops at the ends of said shoulder supports and having portions extending inwardly from the ends of said shoulder supports, pendants depending from the ends of said portions and forming re-entrant angles with said loops, arms issuing from said pendants and extending along one another, fastening means at the ends of said arms for securing the arms together and finger pieces on said arms for engaging and disengaging the fastening means, said finger pieces being disposed in said re-entrant angles.

9. In a garment hanger, a hook, shoulder supports connected to said hook and extending angularly outwardly therefrom, loops at the ends of said shoulder supports and having portions extending inwardly from the ends of said shoulder supports, pendants depending from the ends of said portions and forming re-entrant angles with said loops, arms issuing from said pendants and extending along one another, fastening means at the end of one arm and positioned in proximity to one of said pendants, said fastening means serving to secure the arms together, and a finger piece on the arm issuing from the opposite pendant for engaging and disengaging said fastening means, said finger piece being disposed in the angle between the denoted pendant and the loop from which it issues.

10. In a garment hanger, a hook, shoulder supports connected to said hook and extending angularly outwardly therefrom, arms extending inwardly from said shoulder supports and along each other, one of said arms having a lug extending upwardly therefrom, and located in proximity to the pendant from which said arm issues,

and latching means at the free end of the other arm for engagement with said lug, said latching means being disengageable therefrom upon upward movement thereof.

5 11. In a garment hanger, a hook, shoulder supports connected to said hook and extending angularly outwardly therefrom, arms extending inwardly from said shoulder supports and along each other, one of said arms having an upwardly 10 extending U-shaped portion forming a lug and located in proximity to the pendant from which said arm issues, and latching means at the free end of the other arm for engagement with said lug, said latching means being disengageable 15 therefrom upon upward movement thereof.

12. In a garment hanger, a hook, shoulder supports connected to said hook and extending angularly outwardly therefrom, arms extending inwardly from said shoulder supports and along 20 each other, one of said arms having a lug extending upwardly therefrom and located in proximity to the pendant from which said arm issues and an eye at the free end of the other arm for the reception of said lug, said eye being disengageable from said lug upon upward movement 25 thereof.

13. In a garment hanger, a hook, shoulder supports connected to said hook and extending angularly outwardly therefrom, arms extending inwardly from said shoulder supports and along each other, a connecting member between the ends of said arms farthest from the shoulder supports from which said arms issue, said connecting member forming bights between said 30 connecting member and arms for the endwise reception of garments and fastening means for securing said arms together at the open ends of 35 said bights.

EDWARD SOKOLIK.
